[57] CLAIM

The ornamental design for a cover for rooftop air intake for vehicles, as shown.

DESCRIPTION

FIG. 1 is a left side elevational view of a cover for rooftop air intake for vehicles showing our new design, it being understood that the broken lines are for illustrative purposes only;

FIG. 2 is a greatly enlarged front elevational view of FIG. 1;

FIG. 3 is a right side elevational view of FIG. 2;

FIG. 4 is a rear elevational view of FIG. 2;

FIG. 5 is a bottom front perspective view of FIG. 2;

FIG. 6 is an enlarged top plan view of FIG. 1; and

FIG. 7 is a bottom plan view of FIG. 6.
